UNITED STATES PATENT OFFICE.

JOHN B. BURNS, OF INDIANAPOLIS, INDIANA, ASSIGNOR OF ONE-HALF TO
ELISHA D. EAMES, OF WATERTOWN, NEW YORK.

AUTOMATIC BRAKE-ADJUSTER.

SPECIFICATION forming part of Letters Patent No. 402,503, dated April 30, 1889.

Application filed September 22, 1888. Serial No. 286,091. (No model.)

To all whom it may concern:

Be it known that I, JOHN B. BURNS, of Indianapolis, in the county of Marion and State of Indiana, have invented certain Improvements 5 in Automatic Brake-Adjusters, of which the following is a specification, reference being had to the accompanying drawings, and to the letters of reference marked thereon.

The object of this invention is to preserve, 10 automatically, the adjustment of the brake-shoes to the normal or prearranged distance from the wheels intended to exist when brakes are off, so that upon the wear of the shoes the increased amount of space between the shoes 15 and the wheels will be at once taken up and the original distance between the shoes and wheels existing when the brakes are off re-established. Various devices for effecting such a result have been projected, some of 20 which have attained a greater or less degree of success. Of such may be mentioned Patent No. 352,444, granted November 9, 1886, to John B. Burns, and Patent No. 354,401, granted December 14, 1886, to Elisha D. Eames.

25 My present invention, which embodies the principle set forth in the said two patents, is designed to simplify, cheapen, and render more effective, safe, and reliable the mechanical appliances used.

30 In the accompanying drawings, Figure 1 is an elevation of a pair of car-wheels with their brakes and appendages, showing the application thereto of my invention. Fig. 2 is a perspective view, upon an enlarged scale, of the parts entering chiefly into the invention detached. Fig. 3 is a sectional view of a detail 35 on the line *a b*, Fig. 2. Fig. 4 is a similar section upon the line *c d* of the same figure.

Similar letters of reference indicate similar 40 parts of the invention in the respective figures.

A A show parts of the truck-frame, and B B the car-wheels.

C C' are the brake-beams suspended by the links *c* to the truck-frame.

45 D D' are the brake-levers, and E is the lower brake-rod uniting them.

F is the rod connecting the upper end of the brake-lever D' to the diaphragm, piston, winding-staff, or other agent for the application 50 of power.

All of said parts and devices may be of any ordinary or approved construction.

The lower end of the brake-lever D is pivoted to the lower brake-rod, E, the lever carrying the brake-beam C in the ordinary manner. 55 The other brake-lever, D', which carries the brake-beam C', is pivoted to a short connection, F', the outer end of which is forked to receive the end of the lever. The connection F', as seen in the cross-section, Fig. 3, is channeled for the greater part of its length to a depth and width equal to the size in cross-section of the lower brake-rod, E, which fits and is adapted to slide therein. It is not necessary, however, that the bottom should be 60 closed, as it may be entirely open, except for so much of the length at the inner end of the connection F' as may be required to hold it together and for strength. The inner end of the connection is shaped as seen in the cross-section, Fig. 4, and in Fig. 2—that is to say, it forms a strap, shackle, or close bearing, *f*, entirely, but loosely, surrounding the rod E.

H is the link or rod pivoted at its outer end to the brake-lever D' by the pin *d*. The said 75 end of the link or rod H is forked, as at *d'*, to straddle the lever D', and the fork is provided with a slot, *d''*, in which the pivotal pin *d* is adapted to have a movement equal to the predetermined distance between the brake-shoes 80 and the wheels when brakes are off. The inner end of the link or rod H is furnished with a strap or shackle, *h*, which fits loosely over the lower brake-rod, E, and is adapted to work 85 thereon, as hereinafter described. It will be understood that the opposite end of the lower brake-rod, E, is pivoted to the brake-lever D.

The inner end of the short connection F' is provided at its lower side with a hooked bracket or projection, *f''*, with its cavity turned 90 up, in which the lower end of a steel link, I, surrounding the brake-rod E rests, while the corresponding end of the link or rod H carries a similar hooked projection, *f'''*, but with its cavity turned down, in which the upper 95 end of a second steel link, I', (also surrounding the brake-rod E,) rests. The steel links are preferably accurately fitted to the sides of the brake-rod E, so as to admit of no lateral play, but are permitted to have a slight 100

swinging movement in the cavities of the hooked projections $f^2 f^3$, as will be more particularly pointed out.

The operation is as follows: The distance which the brake-shoes are designed to move in setting the brakes is, as has been stated, the distance which the pin d is capable of moving in the slot d^2 of the rod H . It is therefore seen that so long as the brake-shoes (they having been adjusted to have the required movement) are unworn the lever D will, in the act of setting the brakes, only move a distance sufficient to carry the pin d the length of the slot d^2 , and the link or rod H will therefore not be moved; but wear of the shoes having occurred, in order to bring the shoes up to the wheels a greater movement of the lever D' becomes necessary, when the link or rod H being drawn upon and the strap or shackle H moving upon the brake-rod E , the steel link I' is diverted from its vertical position on the brake-rod to an inclined position, swinging, as it were, in the cavity of the hooked projection f^3 and binding the top edge of the brake-rod E , shifting it toward the lever D' , and consequently shortening the connections between the brake-shoes, taking up the slack, and restoring the distance which normally existed between the shoes, when off, and the wheels. The other steel link, I , acts exactly in the reverse manner, viz., to grip the brake-rod E and prevent its back movement upon the back motion of the lever D' . It will be seen that the action is entirely automatic, and that the prescribed

movement of the brake-shoes in the act of 35 braking is always maintained.

The movement of the brake-rod E toward the lever D' is checked by the end of the rod striking a pin, i , standing across the forked end of the short connection F' , while the 40 movement of the brake-rod E in an opposite direction is limited by its pin i' coming in contact with the shoulder k of the short connection F .

Having described my invention, I claim— 45

In a brake mechanism, a brake-lever, a short connection pivoted thereto, a brake-rod adapted to slide upon the short connection, a rod pivoted by means of a slot and pin to the brake-lever, and having at its inner end a strap or shackle, combined with a link surrounding the brake-rod and in loose engagement at its upper end with said shackle, and a second similar link also surrounding the 50 brake-rod, but in loose engagement with the inner end of the short connection, substantially as set forth, the first link being adapted to grip the brake-rod as the brake-lever is moved to shorten said rod and the second link to detain the brake-rod and prevent its 55 return movement upon the opposite motion of the brake-lever, as described.

In testimony whereof I have hereunto set my hand and seal.

JOHN B. BURNS. [L. S.]
